GROUND CLAMP

George C. Thomas, Jr., Elizabeth, and Walter H. Weber, Metuchen, N. J., assignors to The Thomas & Betts Co., Elizabeth, N. J., a corporation of New Jersey

Application June 7, 1951, Serial No. 230,358

13 Claims. (Cl. 339—246)

1

The invention relates in general to a connector for connecting two conductors in mechanical and electric relation, especially when disposed in parallel, spaced-apart relation, and, specifically, the invention relates to a ground clamp for connecting a ground wire, usually of small diameter, to a grounding conductor of very large diameter, usually a water pipe. More definitely identified, the invention relates to an improvement in pressure connectors of the water pipe type where both of the conductors are clamped simultaneously between a pair of pressure jaws by the action of a single screw bolt operative to squeeze the conductors between the jaws.

It is a commercial requirement of such connectors that they be made to accommodate pipes, wires and other conductors of different sizes, so that, irrespective of their relative sizes, of course within the capacity of any one set of sizes of connector, a firm and extensive electrical and mechanical engagement be provided between the connector and both of the selected conductors. While such connectors as now known can be designed to fit any one particular size of either of the two conductors, they have not been designed with the intent of providing a fashion-fit to both conductors and at the same time made rigid in order to eliminate springing or other deformation of the clamping structure. In general, particularly considered from an economic standpoint, while such connectors must be made compact and rugged, they must also be designed with the use of the least possible amount of the expensive conductive metal necessary in such devices to function efficiently; the component parts should be few in number, preferably as castings designed to be easily manufactured, free of expensive machining, and easily and quickly installed in place on various size conductors even by unskilled labor.

The primary object of the invention is to provide a connector of the clamp type above outlined, which will be free of the objections heretofore raised against known forms of similar devices and which will at the same time respond to the above-outlined commercial requirements.

Still another object of the invention incidental to the objective of providing a compact form of connector is to streamline the same in order to eliminate as far as possible flanges and like extensions which if struck accidentally might result in enough deformation to loosen the contact pressure on one or both of the conductors.

The disclosure particularly features a form of clamp, the jaw-forming elements of which are

2

simple bronze castings which effect a minimizing in the amount of material used compared to known forms of similar clamps and wherein the material, while limited in its mass or weight, is apportioned to strengthen those parts which are most liable to be subjected to rupturing strains and to provide for mutual reinforcing of adjacent parts, leaving the cross section of material therein unreinforced in the parts where such strains are least liable to occur.

The pipe-engaging parts of the jaw members of the embodiment of the invention herein disclosed feature a form of clamp which provides for at least a four-point contact with the pipe, two points for each jaw engaging the pipe, irrespective of small variations in its diameter, and which, while providing the necessary area of electric contact required of such devices, will minimize any possibility of crushing the pipe, especially when the pipe is relatively frail, as when made of thin gauge copper tubing.

Another object of the invention is to provide in a single pair of jaws a disposition of contact teeth which will form circumferentially spaced-apart contact points around the circumference of different sizes of conductors to direct squeeze forces on any size for the time being in place in balanced relation along lines substantially at right angles to each other and passing through the axis of the conductor engaged thereby.

Various other objects and advantages of the invention will be in part obvious from an inspection of the accompanying drawings and in part will be more fully set forth in the following particular description of two forms of device embodying the invention, and the invention also consists in certain new and novel features of construction and combination of parts hereinafter set forth and claimed.

In the accompanying drawings, Fig. 1 is a perspective view of a water pipe clamp constituting a preferred embodiment of the invention, showing a cable clamping extension, with a pair of conductors, specifically, a thin wall water pipe and an armoured ground wire, clamped thereby, with the conductors shown in ghost outline and with the ground wire shown solid.

Fig. 2 is a plan view of the clamp shown in Fig. 1, with the conductors omitted and with the top member partially broken away to show in plan the lower groove of small radius.

Figs. 3-6 are views in side elevation of a modified form of clamp with the cable clamping extension of Figs. 1 and 2 removed to show the jaw-

forming parts in side elevation as viewed from the line 3—3 of Fig. 2; Fig. 3 being an explanatory view of the tooth arrangement; Fig. 4 showing the jaws engaging a small diametered rod in place of a pipe; Fig. 5 showing the jaws engaging a medium size water pipe; and Fig. 6 showing the jaws engaging a large size water pipe.

In the drawings there is shown a ground clamp 10 formed solely of three separately formed parts factory-assembled to form a unitary article of manufacture. Two of the parts 11 and 12 are rugged bronze castings and the third part is a steel screw bolt 13 of standard design available for purchase on the open market. One of the parts 11 will be referred to hereinafter as a body, and the other part 12 as a cap.

In the illustrated showing, the body is the upper of the two parts and is provided on one side with an integral and lateral extension 14 which may be omitted when its function is not desired. The clamp will first be described, ignoring this extension and thus describing a simplified form of clamp particularly designed for use with a bare ground wire instead of the shielded cable shown in Fig. 1. The part of the body, except the extension, forms an upper jaw-forming member 15 and all of the cap 12 forms a lower jaw-forming member. The jaw members 12 and 15 are of greater length than width, are of somewhat similar configuration, and each is arched slightly in side elevation with the concaved sides facing each other. The jaw members are each of the same material width as viewed in plan in Fig. 2 and are of comparatively small cross section of material except at their long marginal edges hereinafter described.

The inner side of each jaw member which faces the other is provided at one end with a transversely extending concave recess 16 of relatively large radius, and at the other end with a transversely extending concave recess 17 of quite small radius. The large recesses 16 of the two jaw members are in opposing relation and are designed to accommodate therebetween a conductor of large diameter, such as the pipe P or rod R. Similarly, the recesses 17 of small radius are in opposing relation and designed to accommodate therebetween a ground wire W of small size. In the illustrated case the jaw members are each about one and three-quarter inches long, and eleven-sixteenths inch wide; the pipe P (Fig. 5) is a half-inch copper tubing water pipe, but the clamp is designed so that it can equally take a small rod (Fig. 4) or a three-quarter inch pipe as shown in Fig. 6. The wire W illustrated is number 4, but the clamp can equally take a number 6 or 8 size wire.

Opposite ends of the jaw members 12 and 15 are provided with loose interlocks which tend to restrain relative lateral shifting of the jaw members when in their conductor-clamping position and at the same time permit relative adjustment of the jaw members in the direction of their clamping movement to permit them to fit the conductors for the time being in use. For this purpose the opposite ends of the jaw member 15 are each bifurcated to form slots for receiving lugs formed as extensions from the jaw-forming member 12. More specifically described, the end of member 15 which has the large recess 16 is formed of a pair of long, hook-like bifurcations 18 curved in side elevation and forming a long slot 19 therebetween. Similarly, the end of member 15 which has the recess of small

radius is formed of a pair of relatively short bifurcations 20 forming therebetween a short slot 21.

The jaw member 12 is provided at one end with a long, narrow lug 22 curved in side elevation, forming an extension in prolongation of the member 12 and loosely extending into the long slot 19 when the pipe P is of sufficiently small radius to permit such intrusion as shown in Fig. 4. In those cases where the pipe is large the lug 22 is apt to be entirely outside of the slot 19 as shown in Figs. 5 and 6. Similarly, the jaw member 12 is provided at its other end with a lug 23, shorter than the lug 22, in prolongation of the member 12 and extending into the slot 21.

The deep recess 16 in the member 15 is formed partly in the lower face of the two bifurcations 18 and partly in the adjacent inner portion of the lower face of the member 15 up to the bolt 13. The deep recess 16 in the member 12 is formed partly in the upper face of the lug 22 and partly in the adjacent inner portion of the upper face of the member 12 up to the bolt 13.

The recess 17 in the member 12 is formed at the base of the lug 23. The lug 23 faces and sometimes extends into the slot 21 in such way that with the wire W in place and when a squeeze load is imposed on the jaw members the lug 23 tends to snub or slightly bend the part of the wire which is bridged across the slot 21 formed between the pair of bifurcations 20.

The lower jaw member 12 is provided at opposite edges with a pair of depending marginal flanges 24 of relatively small depth, each of which extends along the sides of the long lug 22 and along the member 12 to a thick portion 25 adjacent the associated recess 17. The structure between the long lug 22 and the thickened portion forms in effect a wide web 26 with marginal flanges which tend to reinforce the relatively thin web against bending strains. Similarly, the upper jaw member 15 is provided along its opposite edges with a pair of upstanding, marginal reinforcing flanges 27 which extend along the outer edges of bifurcations 18 to a thickened portion 28 of the member 15 adjacent the associated recess 17. The member 15 is also provided at its opposite edges and between the recesses 16 and 17 with a pair of depending, integral, marginal flanges 29 which tend to provide additional reinforcement in the short lever-forming part of member 15 between the line of thrust provided by the bolt 13 and the small recess 17. This structure likewise provides in the region of the bolt 13 a web 30 reinforced at its edges by flanges 27 and 29. The outer side faces of flanges 24 are provided with V-shaped pockets 31 for receiving the lower pointed ends 32 of the depending flanges 29 to resist relative transverse movement of the jaws when the flanges 24 and 27 are in lapping relation as shown in Figs. 4 and 5.

The somewhat flat portions of the webs 26 and 30 which lie between the recesses 16 and 17 are provided, respectively, with aligned bolt holes 33 and 34. These bolt holes are elongated in the direction lengthwise of their associated jaw members.

The screw bolt 13, which in the illustrated case is about one and one-half inches long, is passed loosely through the aligned bolt holes. The bolt includes a threaded shank 35 provided with a head 36 and a square nut 37 bearing respectively on the webs of the members 12 and 15. The nut is held from rotating with the shank

by reason of its loose fit between whichever of the marginal flanges 24 or 27 it may happen to be contained. The lower end of the bolt shank is peened after it is installed to provide a captive bolt and in this way defeat possibility of the parts becoming permanently separated.

The outer portions of jaw members 12 and 15 which outline, respectively, the bolt holes 33 and 34 form pressure seats 38 and 39 for engagement by the flat under sides of either the head 36 or the nut 37. These pressure seats are formed between their associated marginal flanges and are arched outwardly and longitudinally with the outermost lines or crowns of the arches of each member in transverse alignment to provide a line-like form of pressure seat for each member. By this means and regardless of the size of wire or pipe clamped, and thus regardless of whatever angle to the jaw members may be assumed by the bolt, the screw head and the nut each always rests on the pressure seats of the jaw members at or near, respectively, the screw head or the nut center. Particularly in the case of the screw head the contact along a radial line through the center of the head is much more efficient and provides a better clamping pressure with the various inclinations of the bolt than would be the case if the screw head contacted only at one edge of a flat pressure seat.

The recesses 16 which are fashioned for engagement with the pipe P or rod R are preferably serrated in a novel way. In the form illustrated each recess 16 is curved on a double radius and is otherwise designed to provide a fit on pipes or rods having different diameters and to contact either a large size or a small size conductor along at least four lines, two on each jaw member.

Each member is provided at its recess 16 with two sets of transversely extending teeth with one set separated from the other by a wide, transversely extending groove 40. The teeth which form the outer set 41 and which are contained partly in the inner faces of the long bifurcations 18 and in the inner face of the associated long lug 22 and partly in the adjacent part of the inner faces, have their tooth ridges or points 42 in the arcs of a circle of relatively short radius R' and struck from a center on the axis a—b, bisecting the opening between the jaws and passing through the center of the wire W as shown in Fig. 3.

The teeth which form inner set 43 which lies in the inner faces of the jaw members 12 and 15 close to the bolt 13 have their ridges or points 44 each in the arcs of circles of relatively longer radius R² and struck on arcs whose centers C' are also on the axis a—b, but spaced a short distance outwardly from the center of C as shown in Fig. 3.

In the illustrated case the upper jaw has five teeth in the set 41, designated from left to right as a, b, c, d, and e, while the lower jaw has six teeth designated as a', b', c', d', e', and f'. The set 43 has in both the upper and lower jaws two teeth designated, respectively, g, h and g', h'.

Where the pipe is extremely large, say, slightly larger than the showing in Fig. 6, it is possible that the portion of the bolt which bridges across the space between the jaw elements will form a stop for limiting the lateral movement of the pipe in the direction towards the conductor W. These pitch circles are each considered as in the longitudinal, medial plane of the jaw members when in clamping position.

As to which teeth engage the conductors therein depends upon the diameter of the large conductor for the time being clamped by the jaws. In all cases at least two points of each jaw, or 5 a total of four points, engage the large conductor. The small rod R (Fig. 4) which has a diameter substantially equal to the radius R' is engaged by the four teeth on opposite sides of the recess 40, to-wit, teeth e and g of the upper jaw and f' and g' of the lower jaw. This means that the bearing points of the engaging teeth are grouped about the center of the rod R approximately 90 degrees apart, thus equally spaced apart, two on each of the opposing sides of the rod R. In the case of the medium size pipe (Fig. 5) six points are employed, to-wit, c, d and h of the upper jaw and d', e' and h' of the lower jaw. In this case, the bearing points h and h' of the engaging teeth are spaced about 90 degrees apart 10 and the mean average spacing of the other bearing points of the set 41 therefrom is approximately 90 degrees, so that, here again, the bearing points are more or less equally spaced apart, at least two on each side of the axis a—b passing 15 through the center of the pipe P. The points not mentioned in each case are spaced outwardly clear of the adjacent portion of the perimeter of the pipe or rod.

In the case of the larger size D (Fig. 6), nine 20 points, to-wit, a, b, c and h of the upper jaw and a', b', c', d' and h' of the lower jaw, bear on the pipe P'. In this case, as in Fig. 5, the bearing points h and h' are circularly spaced about 90 degrees apart and diametrically opposite each of 25 these points two or more teeth bear on the pipe so that, here again, the contact points are at least substantially spaced 90 degrees apart.

It is thus seen that, irrespective of the diameters of the pipe or rod for the time being in place, 30 the points of contact of the teeth are at least two on each jaw and the perimeter is engaged at four more or less equally spaced-apart points. In this way the same clamp can be used for widely different sizes of pipes.

In operation and assuming that the nut has 35 been retracted sufficiently to permit the jaw members to separate from or to hang loose on the bolt, the jaw members are slipped over the pipe or rod and located to bring the same into the space 40 between the large recesses 16. The bolt is advanced partly towards its clamping position at least sufficient temporarily to hold the clamp loosely on the pipe. An end of the wire W is then inserted endwise into the space formed between the smaller recesses 17. At this time, the 45 jaw members are free to rock on the pipe as a fulcrum and thus separate the recesses 17 sufficiently to pass the wire W therebetween. When the clamp jaws are moved towards each other, even manually, they will tend to adjust themselves to at least an approximate fit with both the pipe and wire. By means of a screw driver the slotted head is rotated until the squeeze pressure 50 imposed by bolt 13 firmly binds the clamp 10 first on one and then on the other of the conductors P and W. The squeeze pressure is apportioned largely on the wire W by reason of the relatively short length of leverage effort between the line of thrust l—t of the bolt and the center of the wire W. The proportionate lesser pressure is provided by reason of the relatively long length 55 of leverage between the line of thrust and the center of the pipe P, but in any case this is sufficient to grip the pipe firmly without deforming 60 75

it even though it may be made of thin gauge copper.

Reverting to the lateral extension 14 which, with the basic parts previously described, may be considered as another embodiment of the invention, this form is particularly designed for use where the wire W, either of the solid or stranded type, is contained in either a metal shield S or a covering of insulating material.

The extension 14 is a hollow cylindrical tube 10 whose bore 45 is dimensioned sufficiently large to receive the shield when cut back to expose the naked end of wire W. The bore 45 is coaxial with the center of the wire-clamping space provided by the opposing recesses 11 and at its inner end forms an annular stop wall 46 through which the bare wire extends. A steel binding screw 47 is threaded through a side of the extension 14 to engage the shield S or the insulating covering therein when in end-abutting engagement with the wall 46. In this case, the cable with its shield cut back to expose its conductor W is threaded with the wire W in advance through the open end of the extension until the shield or insulation abuts the stop wall, after which the screw 47 is first tightened and then the bolt 13 tightened as previously described.

We claim:

1. In a device of the class described, the combination of a pair of jaw-forming members having at one end of the device opposing free ends and at its other end provided with means for clamping a ground wire, one of the members being bifurcated at its free end to form a slot and the other member provided at its free end with a lock-like lug forming an extension in prolongation of said other member and intruding loosely into the slot to restrain relative lateral movement between the members, the member having the bifurcated free end provided on the side facing the other member with a transverse concave recess contained at least in part in the bifurcated end, and the free end of the other member which has the lug provided with a concave recess contained at least in part in the lug, said recesses being in opposition to each other and fashioned for receiving therebetween conductors of different diameters, said recesses being formed as two arcs of circles considered in the medial longitudinal plane of the jaw members and said recesses being of different radii, the arc of the circle in that part of the recess which is in the bifurcated end and in the lug having a radius slightly smaller than the circle whose arc defines the parts of the recesses remote from the free ends.

2. In a device of the class described, the combination of two jaw-forming members, each provided in the side facing the other with two transversely extending concave recesses, one of larger radius than the other, the recesses of larger radius facing each other to receive therebetween a conductor of large diameter and the recesses of smaller radius facing each other to receive therebetween a conductor of small diameter, the members provided with aligned bolt holes each elongated in the direction of the lengths of its associated member and located nearer the recess of smaller radius than the recess of larger radius, and a screw bolt passed loosely through the bolt holes for clamping the members onto conductors located in said recesses, the recesses of larger radius provided with two sets of inwardly facing teeth having a concaved recess spacing

the two sets apart, the points of the teeth of each set located in the arcs of two circles both considered in the longitudinal medial plane of the jaw members, the points of the teeth forming the set nearest the screw bolt being in the arc of a circle having a slightly larger diameter than the arc of the circle which contains the points of the teeth of the set at the free outer part of the jaw members remote from the screw bolt.

3. A clamp for clutching pipes of different external diameters and including two jaws pivotally related at one end, each of said jaws provided adjacent its other end with a concaved recess, and the two recesses disposed with their concaved sides in opposing relation and coacting to clamp a pipe therebetween, a bolt located between the pivoted ends and the recesses for extending a squeeze load on the jaws, each of said concaved recesses provided with transversely disposed teeth of V-form disposed in parallel relation, arranged in two sets with a blank groove therebetween, the points of the teeth of the set nearest the bolt defining an arc of a circle of large radius and the points of the teeth of the other set being more than three equidistantly spaced apart and defining an arc of a circle of relatively smaller radius.

4. A clamp for clutching conductors of different external diameter, including a pair of coacting jaws, means at one end of the clamp for pivotally connecting the jaws, said jaws having opposing concaved recesses at their other end for receiving therein conductors of different diameters, said opposing recesses being on opposite sides of an axis extending through the pivotal connection, each recess provided centrally thereof with a concaved groove and on opposite sides thereof with two sets of parallel transversely extending V-teeth, the points of the teeth of one set being tangent to the arc of a circle of relatively large radius and whose center is in said axis, and the points of the teeth of the other set being tangent to the arc of a circle of relatively smaller radius and whose center is in said axis, the number of teeth tangent to the arc of smaller radius being greater than the number of teeth tangent to the arc of larger radius, and a screw bolt for acting on the jaws, said bolt being disposed adjacent said axis and nearer the set of teeth of smaller number than the teeth of greater number.

5. A jaw clamp including a pair of jaws pivotally connected at one end, each having a recess in its work face adjacent its other end, each of said recesses defined by a plurality of V-teeth disposed in parallel relation transversely of the length of the jaw and arranged in two sets, the teeth forming the set adjacent said end being more than three in number and having therein points tangent to the arc of a circle of relatively small radius and the teeth forming the other set adjacent the pivotal connection being less than three in number and having their points tangent to the arc of a circle of relatively large radius and with the centers of said circles spaced apart from each other and from the axis of the pivotal connection.

6. A clamp for clutching conductors of different external diameters, including a pair of jaws of similar configuration and provided with means for pivotally connecting them at one end, each of said jaws provided at its other end with a concave recess, each of said recesses provided centrally thereof with a concave groove and on opposite sides thereof with two sets of parallel

transversely extending teeth, the teeth of the set nearest the pivotal connection in both jaws being two in number and tangent to a circle whose center lies in an axis located between the jaws and passing through the pivotal connection, the teeth of the other set on one of the jaws being five in number, and the teeth of the other set on the other jaw being six in number, and with both the five and six toothed sets tangent to a circle whose center is also on said axis and whose radius is shorter than the radius of the circle to which the two toothed set is tangent and with the teeth of each set equidistantly spaced apart.

7. A clamp of the pressure type for mechanically and electrically connecting a small diameter wire to a conductor of relatively large diameter, including two jaws formed of highly conductive metal arcuate in side elevation and provided at opposite ends with a projection from the end of one jaw located in a slot formed in the adjacent end of the other jaw to provide loose interlocks at opposite ends of the clamp, each jaw comprising a long, narrow arcuate web provided at one end with a pair of outwardly projecting marginal flanges, the jaws forming therebetween at said end a recess of relatively large diameter for receiving the large conductor, the jaws at their other ends being each of greater thickness of material and thus more rugged than the first-named ends of the jaws, said ends of greater thickness provided with aligned bolt holes in part formed in that part of the web which defines the large diameter recess, the deep portion of each jaw on opposite sides of its associated bolt hole forming deep, inwardly projecting marginal flanges in part defining said ends of greater thickness, with the flanges of one jaw lapping the flanges of the other jaw to resist relative lateral movement when the flanges are in lapping relation, and said jaws in their region of greatest thickness and adjacent the contiguous end interlock provided with registering recesses of relatively small diameter forming a space for receiving the wire, and a single bolt passed through the bolt holes, located between the recesses of large and small diameter and located close to the registering recesses of small diameter for squeezing the jaws into engagement with the conductor and the wire.

8. The clamp defined in claim 7, wherein the outer sides of the flanges of one of the jaws are provided on opposite sides of the associated bolt hole with a pair of inwardly-facing pockets and the flanges of the other jaw are each provided with a pointed end, with the pointed ends adapted to be received in the pockets when the flanges are in lapping relation and operative in close proximity to the bolt to supplement the end interlocks to resist relative transverse movement between the jaws.

9. The clamp defined in claim 7, wherein the bolt holes are elongated in the direction of the length of the jaws and are located between the flanges, and wherein the outer faces of the webs in the portions thereof which outline the bolt hole provide elongated pressure seats for receiving squeeze pressure from the bolt and which seats lap the thick portions in which the recesses of small diameter are located, and a non-circular nut on the bolt located between the flanges of one of the jaws, said nut being of greater dimension in one diametral direction than the distance between said flanges and held thereby from rotating with the bolt.

10. The clamp defined in claim 7, wherein the

webs in the parts which form the pressure seats are each arched outwardly and longitudinally with the outermost crowns of the arches in mutual transverse alignment to provide a line-like form of contact on the pressure seat of each jaw adapted to be engaged by either the head or nut of the bolt in the bolt holes.

11. A clamp including two long, narrow jaws in superposed relation and provided at opposite ends with loose interlocks each operative to prevent relative transverse movement of the jaws, the jaws at one end of the clamp being arcuate, of relatively least thickness of material and with their concave sides facing each other and forming therebetween a recess of relatively large cross section, each of the jaws increasing in thickness of material from said least thickness towards a maximum thickness adjacent its other end, the material of each jaw being massed largely in the part forming said other end thereby to give increased strength to said other end, the inner faces of said other ends at their extreme free ends provided with small opposing channels coacting to form a recess of relatively small cross section, said jaws provided with aligned bolt holes located mainly in the ends of said massed material, and a single bolt passed loosely through the bolt holes for drawing the jaws towards each other and said bolt in the portion thereof which lies between the jaws being exposed to the recesses of both the large and small diameter and thus operative to define and limit the adjacent ends of said recesses.

12. A clamp for electrically and mechanically connecting a small diameter wire to conductors of relatively large diameters and of different sizes, including two opposing long arcuate jaws of somewhat similar configuration provided at opposite ends with a projection from the end of one jaw adapted to be located in a slot formed in the adjacent end of the other jaw to provide loose interlocks at opposite ends of the clamp, each interlock operative when its projection is within its slot to resist transverse shifting of the associated end of the jaws, the jaws at one end of the clamp provided with opposing recesses of relatively large diameter for receiving therebetween a relatively large conductor and said jaws at their other end provided with opposing wire-receiving recesses of relatively small diameter, said jaws provided in the parts thereof which lie between the recesses with a projection from one in opposition to a recess in the other and said recess fashioned to receive the projection and said projection and recess coacting when in lapping relation to resist relative transverse shifting of the jaws, and a screw bolt passed loosely through the jaws adjacent said projection and recess to force the jaws towards each other.

13. A connector for use in mechanically and electrically connecting two conductors, one of relatively large size and the other of relatively small size, comprising three separate parts, two of the parts being of highly conductive metal and forming a pair of coacting jaw members free of each other for relative adjustment, and the third part forming a connecting screw bolt, the jaw members being each of arcuate form in side elevation, each jaw member provided at one end thereof and on the side thereof facing the other member with a transversely extending concave recess, with the recesses facing each other and providing a space therebetween for receiving the larger of the two conductors, the opposing concave faces of said recesses being each provided

with two sets of teeth extending transversely of its associated member, with the sets spaced apart and operative for gripping said larger conductor at two circumferentially spaced-apart points, and each jaw member provided at its other end with a relatively small recess and with said small recesses coacting in opposing relation to receive therebetween the conductor of relatively small size, one of the jaw members provided at opposite ends thereof with a lug projecting therefrom, the other jaw member having its ends bifurcated to form slots, each slot adapted to receive its associated lug to form a loose interlock at each end of the connector, both jaw members provided at the end which has the larger recess with an outstanding marginal reinforcing flange which extends on one of the jaw members to the end of the associated lug and on the other jaw member to the ends of its associated bifurcated portion, each jaw member provided at the end of the connector with the small recesses with a flange from one projecting inwardly towards a flange of the other, one of said flanges terminating in a lower pointed end adapted to be received in a pocket formed on one side of the other flange and said pointed end and pocket operative to resist transverse shifting of the jaw members, and said jaw members provided in the part thereof which lies

between the two conductor-receiving recesses and adjacent said pocket and pointed end and partly within the region which forms one end of the larger transverse recess with aligned bolt holes, 5 said holes being elongated lengthwise of the jaw members and through which bolt holes the connecting screw bolt passes, and said outstanding flanges of each jaw member adapted to receive therebetween a nut on the bolt and operative to resist rotation of the nut with the bolt.
